UNITED STATES PATENT OFFICE.

JOHN D. STANGE, OF SAN FRANCISCO, CALIFORNIA.

DESIGN FOR A LADY'S HAT.

SPECIFICATION forming part of Design No. 22,766, dated September 5, 1893.

Application filed August 14, 1893. Serial No. 483,143. Term of patent 3½ years.

To all whom it may concern:

Be it known that I, JOHN D. STANGE, a citizen of the United States, residing in the city and county of San Francisco, State of California, have invented and produced a new and original Design for Ladies' Hats, of which the following is a specification, reference being had to the accompanying drawings, showing a part thereof.

10 Figure 1 is a side view of the hat. Fig. 2 is a perspective view of the same.

15 The leading features of my design consist of a horizontal crown or disk projecting beyond the body all round, and a straight horizontal visor projecting from the bottom of the body toward the front and parallel with the crown.

20 A is the body of the hat which is approximately cylindrical in its general contour, and B is the crown in the form of a single circular flat disk secured to the top of the body, so that its periphery projects equally all around the top of the body and at a considerable distance beyond it.

25 C is the visor which fits around the front portion of the bottom of the body and projects horizontally forward therefrom and in a plane approximately parallel with the crown.

Having thus described my design, what I claim is—30 The design for hats herein shown and described, the same comprising the cylindrical vertical body, the horizontal circular single disk crown projecting beyond the upper periphery of the body, and a horizontally projecting visor approximately parallel with the crown as set forth.

35 In witness whereof I have hereunto set my hand.

JOHN D. STANGE.
